UNITED STATES PATENT OFFICE

2,424,740

SHAPED FEATHERBONE MATERIAL AND
PROCESS FOR MAKING SAME

Frederic W. Chamberlain and Anthony J. Klute,
Three Oaks, Mich., assignors to The Warren
Featherbone Co., Three Oaks, Mich., a corpora-
tion of Michigan

Application January 27, 1944, Serial No. 519,874

5 Claims. (Cl. 2—258)

1

This invention relates to feather quill material made in accordance with the teachings of certain prior patents to Warren, Nos. 559,827 of May 12, 1896, 311,621 of February 3, 1885, and 550,855 of December 3, 1895.

Among the objects of the present invention are to provide a supporting or stiffening material having a nonlinear portion having resilient characteristics such that the nonlinear portion will return to its set nonlinear condition when deformed therefrom, and wherein the material is formed of slivers of feather quills disposed in substantial parallelism and suitably bound together so as to provide a relatively stiff, resilient, set, structure of relatively small cross section; to provide various configurations of featherbone material set to a shape which is either wholly or partly nonlinear and which nonlinear portions possess inherent resiliency such that when deformed from their permanent set they will return to such set; to provide a process for manufacturing such shaped resilient featherbone material; to provide these and other objects of invention as will be apparent from a perusal of the following specification when taken in connection with the accompanying drawings, wherein:

Figure 1 is a view of a single adaptation of the multifarious adaptations of the present invention;

Figure 2 is a rear view of the adaptation shown in Figure 1;

Figure 3 is a view showing the upper portion of the curved featherbone form attached to the pair of overalls shown in Figures 1 and 2;

Figure 4 is a view of still another form of the present invention;

Figure 5 is a view of yet another form of the invention;

Figure 6 is a view showing the manner of attaching one end of the form shown in Figure 4, 40 to the overalls;

Figure 7 is a view of a piece of straight featherbone material before it is given its permanent set or shape in the manner set forth in the present invention;

Figure 8 is a view of the tank or other means for softening the untreated cords or blades sufficiently to render the glue sizing in the featherbone soft and sticky;

Figure 9 is a view of a drying mechanism used in heating the softened form after it is applied to a mandrel to give the form the requisite shape;

Figure 10 is a view showing the step of applying the sizing solution to the top side of the featherbone after it has been dried on a form;

2

Figure 11 is a view showing the coiled featherbone removed from the mandrel, and being heated after coating;

Figure 12 is a view showing the manner of applying waterproofing to the form after the sizing has been applied thereto;

Figure 13 is a cross sectional view taken transversely of the form shown in Figures 4 and 5;

Figure 14 is a view showing the featherbone 10 in the form of a curved rod; and

Figure 15 is a view of featherbone having angularly disposed portions.

Heretofore featherbone has been constructed as a stiffening material, being formed in a straight strip and providing qualities of resiliency, the featherbone being used in corsets or in other apparel, or in places where reinforcement is desired in a flexible fashion, and where the material, if flexed out of its straight position, would 20 return to such straight position.

The present invention is concerned with shaped featherbone forms possessing the same resiliency, but which in the process of manufacture are shaped more or less abnormally with respect to 25 the normally substantially straight feather quills or slivers in whole or in part to forms other than straight or linear, such for instance as curved forms or forms with angularly disposed portions, and yet which possess inherent resiliency so that 30 when flexed out of their set curvilinear or nonlinear conformation they instantly return to their set form or shape.

Referring to the drawings, in accordance with the teachings of the prior Warren patents mentioned above, there is first provided a featherbone section 2, such for instance as the flat section shown in Figure 7, preferably but not necessarily, of a section five eighths of an inch in width, composed of slivers or pieces 4 of quill with the feathers removed and suitably interlaced, bound, woven, or stitched with thread, cord, or other tenuous fastening material 6 into the general form shown in Figure 7, which herein is shown as a straight, flat shape of relatively small cross section. During the process this shape is sized with glue and suitably compacted so that the shape is of generally uniform cross section throughout its length.

To form the featherbone shape of the present 50 invention, it is then immersed in a tank 8 of luke-warm water, or otherwise subjected to moisture and heat for substantially three or four minutes to make the glue sizing and the featherbone soft and pliable. Thereafter the featherbone, while 55 it is moist and pliable, is placed upon any suitable

form or mandrel 10, which mandrel is of the required shape. In the present instance the mandrel is curvilinear and forms a part of the circumference of a circle. The featherbone shape is fastened upon this mandrel and allowed to dry thereon. The drying can be expedited by drying the forms while on the mandrel in the heating oven of a drier 12 which is heated by the heating element 14 controlled by the thermostat 16. The temperature is preferably set to be between 90° and 120° F.

After the featherbone is suitably dried on the mandrel, a sizing solution is applied to the outer side of the featherbone on the form. In the present instance the sizing in the shape of shellac is sprayed on as at 18. If desired, any type of waterproofing may be used for this sizing operation, or the sizing may be applied by brushing onto the outside of the form, if desired.

After the featherbone is taken off the forms the inside of the shaped featherbone form is given one or a plurality of coats of waterproofing, which may be applied by brushing on or by dipping. This waterproofing is then dried on the form, either by heating in the oven 12 to the same temperature or otherwise, or by any desirable drying method. This waterproofing solution gives the featherbone form an additional sizing and also a waterproofing coating. The waterproofing, if desired, may consist of dissolved Celluloid scrap with ethyl acetate to which is added commercial alcohol for thinning purposes and for the purpose of making the solution faster drying when dried and run through the heater. After the form is suitably waterproofed and coated it retains its set shaped form and is ready for use.

Figures 1, 2 and 3 illustrate, at 20, one structure of the featherbone material which is shaped to provide a curvilinear or hooked end 22, and at 24 is shown another form illustrated specifically in Figure 4 as applied to the knee portions of an overall, which overall is constructed in the manner shown in Figures 1 and 2. In these forms the lower end of the featherbone form 20 is sewed into a pocket 26 of the upper portion of the overall and the curvilinear form 24 is sewn in the manner shown in Figure 6 into the knee portion 28 of the overall, whereby the overall may be slipped onto the shoulder and knee portions of the wearer and will be held on by the curvilinear portion of the light featherbone shapes.

It will thus be seen that we have provided a new featherbone structure and process for making same, which structure is adaptable for a multiplicity of uses, particularly wherein a light, stiff, pre-shaped, resilient material is needed, and particularly one having nonlinear portions, for instance curvilinear shapes and other shapes of various angularity which when stressed or flexed out of their normal set position, due to their own or inherent resiliency, will immediately spring back to the normal set position.

It is to be understood, of course, that instead of a flat shape, any desired cross section of featherbone may be provided, which includes rods as well as flat shapes. It is also understood that the shapes may have angularly disposed portions as suggested in Figure 15, as well as relatively curved portions, as shown in the various figures of the drawings, and that these set shapes all have inherent resiliency whereby they return to set condition when strained or flexed therefrom.

Obviously the invention is not limited to the specific details of construction disclosed herein but is capable of other modifications and changes

without departing from the spirit and scope of the appended claims.

The invention is hereby claimed as follows:

1. The herein described process which comprises binding together a plurality of substantially parallel, elongated slivers of feather quills, compacting the same with sizing into an elongated body, forming said body, while soft, to a predetermined curvilinear shape, and hardening said body while it is secured on a mandrel, and sizing said body while so shaped, and drying the same.

2. A featherbone structure adapted for use as stiffening or supporting material and including substantially parallel elongated slivers of feather quill, bound together, sized and compacted to a predetermined cross section, and having at least a portion thereof predeterminedly and abnormally shaped relative to the normally substantially straight feather quills and set in such abnormal shape but retaining inherent resiliency whereby to return to abnormal shape upon being flexed therefrom.

3. The herein described process which comprises binding together a plurality of substantially parallel elongated slivers of feather quills, compacting the same with sizing into an elongated body, forming said body while soft to a predetermined shape at least partially non-linear, hardening said body while so shaped, then sizing said body while so shaped, and drying the same.

4. The herein described process which comprises binding together a plurality of substantially parallel elongated slivers of feather quill, compacting the same into an elongated body, softening the elongated body, forming the softened body to a predetermined non-linear shape, hardening the shaped body, and coating the exterior surfaces of the body with a sizing solution, and drying the same.

5. The herein described process which comprises forming elongated slivers of featherbone into parallel relation, binding the same with a tenuous, flexible material, sizing the same into a compact shape of predetermined cross section, softening the bound quill portions and mounting upon a mandrel having faces formed to produce the desired final non-linear shape of the bound quill portions until dry, sizing the exterior surfaces of the featherbone structure while so mounted on said mandrel, and thereafter waterproofing the interior surfaces of the featherbone structure whereby said structure acquires a permanent set and possesses inherent resiliency causing it to return to the set position when flexed therefrom.

FREDERIC W. CHAMBERLAIN,
ANTHONY J. KLUTE.
